CLAIM

The ornamental design for a spreader, as shown and described.

DESCRIPTION

FIG. 1 is a perspective view of the spreader showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1;

FIG. 10 is a partial enlarged view of portion 10 in FIG. 1; and,

FIG. 11 is a partial enlarged view of portion 11 in FIG. 2. The dash-dash broken lines shown in the drawings are included for the purpose of illustrating portions of the spreader that forms no part of the claimed design.

The dash-dot broken lines of FIGS. 1 and 2 depict the limits of the enlarged views and form no part of the claimed design. The dash-dot lead lines in FIGS. 1 and 2 labeled 9, 10, and 11 indicate the areas from which the enlargements in FIGS. 1 and 2 are taken and form no part of the claimed design.
